UNITED STATES PATENT OFFICE.

GEORGE E. VAN DUSEN, OF CLEVELAND, OHIO.

SMOKER'S CONVENIENCE.

1,152,454.

Specification of Letters Patent. Patented Sept. 7, 1915.

Application filed July 6, 1914. Serial No. 849,063.

To all whom it may concern:

Be it known that I, GEORGE E. VAN DUSEN, a citizen of the United States, residing at Cleveland, in the county of Cuyahoga and State of Ohio, have invented a certain new and useful Improvement in Smokers' Conveniences, of which the following is a full, clear, and exact description.

This invention relates to a device which 10 may be termed a smoker's convenience in that it provides a unitary article which functions as a retainer or holder for a box of matches, provides a cigar cutter, and also 15 may be utilized as a shield for protecting a lighted match against being blown out by the wind while the user lights a cigar.

The object of the invention is to form such a device as a compact and inexpensive article.

20 Generally speaking, the invention comprises the elements and combinations thereof set forth in the accompanying claims.

Reference should be had to the accompanying drawings forming a part of this 25 specification in which—

Figure 1 is a perspective view of the device. Fig. 2 is a perspective view of another portion of the device. Fig. 3 is a section transversely of the device, and Fig. 4 is a 30 top plan view with certain portions in section.

The casing comprises side pieces 1 and 2 which are joined to each other by means of a back piece 3, which may be formed integral with the sides 1 and 2 or separately and attached thereto. One end of the casing is entirely open and free to receive a match box, such as represented at 4. At the opposite end the casing has secured thereto a 40 hood 5, this hood being slightly inset, upon both sides, as indicated in the drawings, so as to provide a stop against which the box 4 may abut at the top portion thereof. This hood 5 is open at the rear end, as will be 45 seen, and at the forward end is provided with a circular opening.

Upon the back 3 of the casing there is a 50 knife retaining means or casing 6, which may be secured to the back 3 in any desired manner. This knife casing 6 at one end is provided with a circular opening indicated at 7, which registers with one end of the hood 5, and there is also an opening 8, through which projects a tongue 9, the 55 tongue being secured to the knife 10 for the purpose of reciprocating the knife 10 past

the opening 7. Obviously when a cigar end is inserted in the opening 7 and the knife is reciprocated, the end of the cigar will be clipped, and inasmuch as the opposite end 60 of the hood 5 is open, the cigar tip will fall to the ground.

In the top of the hood 5 there is a V-shaped slot 11. This slot is adapted to receive a match when lighted, as indicated 65 in Fig. 2. The lighted end of the match extends into the hood and with the box 4 pushed down slightly there is sufficient space for the user to insert the end of the cigar to be lighted. The hood 5 and the sides 1 70 and 2 form a protection against the blowing out of the match by the wind.

Upon the free ends of the sides 1 and 2 there are inturned flanges 12 which are adapted to engage the match box 4 and hold 75 it from disengagement with the sides 1 and 2.

Having thus described my invention, what I claim is:—

1. A device of the character described, 80 comprising a casing open at the ends and at one side and adapted to receive a box of matches, a hood portion mounted upon the casing and open at both ends, a cutter blade slidably held upon the casing and adapted 85 to be reciprocated past one end of the hood whereby the end of a cigar inserted in the end of the hood may be severed.

2. A device of the character described, 90 comprising a casing having side pieces provided with retaining flanges at the free edges thereof, and a strip which joins the side pieces, a hood extending from one end of the side pieces, a cutting blade adapted to slide along the strip and to be reciprocated past 95 the end of the hood, whereby the end of a cigar inserted in the end of the hood may be severed by the cutting blade.

3. A device of the character described, 100 comprising a casing having side pieces, flanges at the free edges thereof and stops provided at one end whereby a match box may be held within the said casing, a hood portion extending from one end of the side pieces, a knife casing secured upon the said 105 casing and provided with a circular opening which registers with the hood, a knife within said casing adapted to reciprocate past the opening in the knife casing and the hood whereby the end of a cigar may be 110 severed by the cutting blade.

4. A device of the character described,

comprising a casing open at the ends and at one side and adapted to receive a box of matches, a hood portion extending from one end of the casing, a cutting blade slidably mounted upon the casing and adapted to reciprocate past one end of the hood whereby the end of a cigar inserted in said hood may be severed, said hood also being provided with a means to receive and retain a match stem whereby a lighted match may be shielded from the wind.

5. A device of the character described comprising a casing open at the ends and at one side and adapted to receive a box of matches, a hood portion extending from one end of the casing, a cutting blade slidably mounted upon the casing and adapted to reciprocate past one end of the hood whereby the end of the cigar inserted in the end of the hood may be severed by the cutting blade, said hood being provided with a slot adapted to receive and retain a match stem whereby a lighted match may be shielded from the wind.

20 25. 6. A device of the character described, comprising a casing open at the ends and at one side and adapted to receive a box of matches, a hood portion mounted upon the

casing and open at both ends, a retaining means secured to the casing, a cutter blade 30 held between said retaining means and the casing and adapted to reciprocate past one end of the hood whereby the end of a cigar inserted in the end of a hood may be severed.

7. A device of the character described, comprising a casing having side pieces and a strip which joins the side pieces, a hood extending from one end of said side pieces, the said strip extending to the top of the hood and provided with an opening, a retaining means secured to the casing and extending to the top of the hood and also provided with an opening which registers with the opening in the said strip, a cutter blade 35 40 45 50 slidably mounted between the retaining means and the strip and adapted to reciprocate past the openings in the said retaining means and strip whereby the end of a cigar inserted in the said openings may be severed.

In testimony whereof, I hereunto affix my signature in the presence of two witnesses.

GEORGE E. VAN DUSEN.
